UNITED STATES PATENT OFFICE

119,744

DESIGN FOR A DOOR FRAME

Joseph Erle Druckenmiller, Ardsley, Pa.

Application November 28, 1939, Serial No. 88,523

Term of patent 3½ years

To all whom it may concern:

Be it known that I, Joseph Erle Druckenmiller, a citizen of the United States, residing at Ardsley, in the county of Montgomery and State of Pennsylvania, have invented a new, original, and ornamental Design for a Door Frame, of which the following is a specification, reference being had to the accompanying drawing, forming part thereof, in which:

Figure 1 is a view in front elevation of a door frame showing my design;

Figure 2 is a view in vertical cross-section along line 2—2 of Figure 1; and

Figure 3 is a view in horizontal cross-section along line 3—3 of Figure 1 on an enlarged scale.

I claim:

The ornamental design for a door frame, substantially as shown.

JOSEPH ERLE DRUCKENMILLER.
